UNITED STATES PATENT OFFICE.

GUSTAV EGLOFF AND HARRY P. BENNER, OF CHICAGO, ILLINOIS, ASSIGNORS TO UNIVERSAL OIL PRODUCTS COMPANY, OF CHICAGO, ILLINOIS, A CORPORATION OF SOUTH DAKOTA.

APPARATUS FOR CRACKING OIL.

Application filed August 21, 1920, Serial No. 405,100. Renewed June 9, 1926.

This invention relates to improvements in apparatus for cracking oil. The object of the invention is to provide effective means for continuously removing the precipitated 5 carbon from the system in the process of the so-called continuous type.

In the drawings Fig. 1 is a side elevation partly in section of our improved apparatus. Fig. 2 is a section taken through line A—A 10 of Fig. 1.

Referring to the drawings, 1 designates a furnace provided with burner, 2, firebox, 3, and stack, 4. In this furnace is mounted the heating elements, which may consist of a 15 pair of headers, 5 and 6, connected by a plurality of tubes, 7—7. The raw charging oil may be continuously delivered to the header, 5, through the charging line, 8, connected to any suitable charging pump and supply 20 tanks (not shown). The oil passes out of the header, 6, through line, 9, controlled by valve, 10, to the upper part of a carbon precipitating chamber, 11. This chamber, 11, is provided with a vertically extending partition or septum, 12, which extends from the 25 top of the chamber, 11, down nearly to the bottom thereof, as shown clearly in dotted line in Fig. 1. The vapors and gases which are not condensed in the chamber, 11, pass 30 out through line, 13, controlled by valve, 14, into the lower part of dephlegmator, 15. The vapors condensed in the dephlegmator, 15, are returned by pipe, 16, to the charging line, 8. A valve, 17, is interposed in the line 35 16. The reflux condensate is prevented from falling back into the pipe, 13, by means of a spaced cap member, 18, mounted above that portion of the pipe, 13, which projects into the lower end of the dephlegmator. The 40 upper part of the dephlegmator is connected by line, 19, controlled by valve, 20, to a water condenser coil, 21. This condenser coil, 21, is connected by line, 22, in which may be interposed a valve, 23, to the receiver, 45 24. The receiver, 24, is provided with liquid drawoff pipe, 25, controlled by throttle valve, 26, and gas outlet pipe, 27, controlled by valve, 28. It is also provided with liquid level gauge, 29, and pressure gauge, 30. The arrangement of the valves referred to is such 50 that a uniform pressure may be maintained on the system from the heating element to and through the receiver, or a differential pressure may be maintained on various parts 55 of the system by suitably regulating the

valves. In the event of maintaining a higher pressure on the still than the dephlegmator, the reflux condensate will have to be pumped back to the line, 16, in which case a pump (not shown) must be interposed in the line, 60 16, or else the reflux condensate must be diverted from the pipe, 16, to some other receptacle than the charging line, 8.

The liquid residue in the chamber, 11, together with its precipitated carbon content 65 is constantly drawn off through the rotating valve plug, 31, to delivery pipe, 32. This valve plug is driven through shaft, 33, and gearing 34, by any suitable source of power. The arrangement is such that the carbon 70 precipitating chamber, 11, will be constantly freed of its heavy residue and carbon content, while at the same time permitting the uncondensed vapors to pass freely to the dephlegmator. The oil in the still is preferably maintained in liquid phase so as to prevent carbon precipitation in the still, or, in other words, vaporization takes place in the chamber, 11, where the carbon is thus precipitated. 75

We claim as our invention:

1. An apparatus for treating oil comprising a still having a pair of headers, communicating cracking tubes between said headers, means for feeding oil to one of the 85 headers to pass through said tubes to the other header and to be heated during such passage to the cracking temperature while maintained in a substantially liquid phase, a vertically disposed expansion and separating chamber adapted to receive heated oil after passage through said cracking coils, a vertical partition in said chamber for causing the hydrocarbon material introduced thereto to pass downwardly through the 90 chamber and thence upwardly on an opposite side of said partition, a continuously rotating valve at the lower end of said chamber for discharging liquid oil and precipitated carbon therefrom and a vapor discharge from the opposite end of said header for discharging vapors therefrom. 95

2. An apparatus for treating oil, comprising a tube still through which oil is adapted to be passed and heated, during passage 105 therethrough, to a cracking temperature, a vertically disposed expansion separating chamber, means for delivering heated oil constituents from said tube still to said separating chamber, means within said separat- 110

ing chamber for causing said heated constituents to pass downwardly throughout substantially the entire length thereof and then to rise vertically therethrough, a driven rotary valve at the lower end of said chamber for discharging liquid oil and precipitated carbon therefrom, and means for taking off vapors from the upper end of said chamber.

10. 3. An apparatus for treating oil, comprising a tube still through which oil is adapted to be passed and heated, during passage therethrough, to a cracking temperature, a vertically disposed expansion separating chamber, means for delivering heated oil constituents from said tube still to said separating chamber, means within said separat-

ing chamber for causing said heated constituents to pass downwardly throughout substantially the entire length thereof and then to rise vertically therethrough, a driven rotary valve at the lower end of said chamber for discharging liquid oil and precipitated carbon therefrom and means for taking off vapors from the upper end of said chamber, a dephlegmator for receiving the vapors taken off from said separating chamber, means for returning reflux condensate from said dephlegmator to said tube still, and means for maintaining a superatmospheric pressure on the oil undergoing treatment in the apparatus.
